(57) CLAIM

The ornamental design for a tent for pets, as shown and described.

DESCRIPTION

FIG. 1 is a perspective view of the tent for pets of the present invention;

FIG. 2 is a top plan view thereof;

FIG. 3 is front elevational view thereof;

FIG. 4 is a side elevational view thereof;

FIG. 5 is rear elevational view thereof; and,

FIG. 6 is bottom plan view thereof.

The broken line showing the top spire in FIG. 1 is illustrative of environmental structure only and forms no part of the claimed design.
